CAN AND COVER WASHING MACHINE

Lester J. Williams, Canastota, N. Y., assignor to
 Carl Braun, Inc., Canastota, N. Y., a corpora-
 tion of New York

Application July 15, 1930, Serial No. 468,184

12 Claims. (Cl. 29—84)

My invention relates to can washing mechanism or apparatus and especially to improved mechanism for washing can tops or covers and particularly milk can covers, constructed and arranged to advance the covers in edgewise-upright position; that is, in a position practically at a right angle to the normal position on a can, and to thoroughly wash or sterilize the covers during such advance.

- 10 The present machine also includes means acting automatically after washing the covers, to turn them to horizontal position and deliver them upon the tops of the can bodies which have been advanced and washed in generally parallel 15 relation to the covers and after washing moved to a position beneath the point at which the cover is deposited upon the body, after which the can body with cover thereon is ejected from the machine.
- 20 The characteristics and advantages of the invention are further sufficiently explained in connection with the following detailed description of the accompanying drawings, which show a representative embodiment. After considering 25 this example, skilled persons will understand that many variations may be made without departing from the principles disclosed, and I contemplate the employment of any structures that are properly within the scope of the appended 30 claims.

Fig. 1 is a rear end elevation of a can washing machine designed to wash both can bodies and covers, but showing especially the present improved cover washing mechanism.

- 35 Fig. 2 is a partial side elevation on a larger scale.
- Fig. 3 is a transverse section at 3—3, Fig. 2.
- Fig. 4 is a horizontal section at 4—4, Fig. 2.
- Fig. 5 is a fragmentary view, similar to Fig. 2, 40 showing another operative position.

Fig. 6 is a detail in side elevation, enlarged, showing principally one set of spray pipes, valve and valve operating means.

- 45 Figs. 1 and 2 show essential parts of a can washer in which can bodies are advanced in a linear direction, step by step, and at appropriate positions during advance are washed, and the can tops or covers are advanced in a generally similar manner and in a parallel path at 50 one side of the path of the bodies. The present invention relates principally to improved means for advancing the covers in an edgewise position, that is, in an edgewise direction and in a plane perpendicular to the normal position of the cover 55 when on the can. When so advanced the cov-

ers may be thoroughly washed or scoured by steam or water jets without the necessity for brushing. The machine also includes means acting at the discharge end to turn the covers to horizontal position and then discharge them, each upon the top of a can body which has been advanced, washed and positioned to receive the cover.

The machine is built on or about a generally rectangular, open frame 10 consisting of various upright, longitudinal, and transverse members of angle or channel section, some of the particular frame members being sufficiently referred to hereafter. At the left as the machine is viewed at the discharge end, in Fig. 1, is a passage or trackway 11 and some means for advancing the can bodies step by step. Details of the means for supporting, advancing and washing the bodies are not here shown, except as to certain items referred to hereafter, sufficient to enable the positioning of the bodies to receive the covers, to be understood.

The improved means for advancing the covers includes a longitudinal rail 12 of angle section, and another rail 13 which may be of flat straight strip form and is conveniently identified in some cases as a cam rail. These rails are designed to receive the necks 14 of the can covers 15, while the normally upper faces of the flanged top portions 16 of the covers rest slidingly against horizontal guide rails 17 and 18, which may be of angle section, as shown. As clearly shown in Figs. 1, 2, and 3, the covers are supported in an edgewise nearly vertical position, but tilted slightly from the vertical, as best shown in Fig. 3, to insure resting against the upper or side supporting rails 17 and 18 and prevent accidental tipping until they reach the discharge end without necessity for providing any guides at the side of the cover opposite to rails 17 and 18. For this purpose the lower rails 12 and 13 are supported in a slightly tilted position (Fig. 3) by angle brackets 19 secured to frame cross pieces 20, and the rails 17 and 18 are also supported in slightly tilted or angular positions by uprights 21 of U-brackets 22 which are also secured to the cross pieces 20. The lower rails 12 and 13 are secured to brackets 19 by bolts 23 and spacing sleeves 24. At a suitable plurality of longitudinal positions are the washing or spray pipes, comprising as here shown 50 at opposite positions laterally of the machine, vertical pipes 25 having orifices or nozzles 27 directed toward the normally upper faces of the cover tops 16, and pipes 26 preferably having at a position nearly central in relation to the can 55

covers, horizontal branch pipes 28 connected by a union 29, and these pipes 26 and 28 have orifices or nozzles 30 so directed as to throw jets upon the inner and outer surfaces of the cover collar 5 and under-surfaces of the flanged top, as also sufficiently shown in Fig. 3. For each set of jet pipes, that is, each pipe 25 with its opposite pipe 26 and branch pipes 28, there is a cross-connection consisting of pipes 31 and 32 and a union 33. 10 From each of these unions a pipe 34 connects to a valve 35 and all the valves may be connected as by pipes 36 to a main supply pipe for steam, wash-water or solution; or if desired, a certain number of the valves may be connected to one 15 main supply pipe carrying, say, steam, while others may be connected to another main pipe supplying water for rinsing, etc.

Each valve has a spring-actuated stem 37 and these stems are operated by the short arms 38 20 of levers 39 fulcrumed at 40 on brackets 41 connected to the valve bodies. At a point where the can cover is in centered relation to spray pipes, as best shown in Fig. 6, one of the bottom rails, such as the plain or strip rail 13 has a cam portion 25 or notch 42, so that when in the advance of the cover the collar portion reaches the cam or notch 42 it drops into it and depresses the lever arm 39 to the position of Fig. 6, thus opening the valve and supplying the steam or washing liquid 30 under suitable pressure to thoroughly wash the cover at a plurality of different positions. If desired, the long arms of the levers may have depending portions 43 allowing for hand operation or for counter-weighting. When the can collar 35 is in valve operating position, as just above referred to, it may be additionally supported by the upper flange or rail 12, or in some cases this rail may be omitted and the covers may be entirely supported from below by proper positioning 40 of rail 13.

For advancing the covers step by step from the feed end of the machine in which they are placed by hand, there is a longitudinal, horizontal slide 44 which as shown, is of channel section, inverted, 45 and slidingly supported by a rail 45 and angle brackets 46. At suitable intervals, corresponding to the spacing of the spray pipes, this slide has pivotally mounted at 47 feed pawls or pushers 48 normally held by springs 49 against stops 50 50 on the slide. These pawls engage rearward faces of the can collars and when the slide is reciprocated in the forward direction advance the covers simultaneously, and when the slides move in the opposite direction they snap past the collars of the next rearward covers and reengage with them, 55 and so on, in an obvious way. Return movement of the covers is prevented, and they are also definitely retained in washing positions by pawls or detents, consisting as here shown of the angular portions 51 of bars 52 which may be pivotally connected or loosely mounted and held by stops between longitudinal rails 53 supported on the cross members of the U-brackets 22 previously referred to. These detent bars also have upwardly extending portions 54 provided with 60 weights 55, so that the angular portions of the detents are held in engagement with the can collars and force these collars down into the depressions or notches 42 and into engagement with the levers 39, insuring proper actuation of the 65 levers and valves and also retention of the covers in washing position; and when the covers are advanced the detents are raised to permit such movement and drop behind the covers preventing return movement.

As each cover passes beyond the last detent rod 52 it is brought opposite a pushing or tilting member 56 carried by a short horizontal arm 57 5 removably or adjustably secured at 58 to the upper end of a lever 59 fulcrumed at 60 on a frame upright 61. An upper portion of this lever may also be guided by location in the slotted bracket 62. At this time the cover is also located above a tilting plate or table 63 which is pivotally mounted at 64 on a bracket secured to the main frame and 10 provided with a stop consisting of a rod 66 pivotally connected to the table and passing through a hole in a bracket arm 67 so that the downward tilting movement in Fig. 5 is limited by nuts 68 15 on the stop rod engaging below the bracket arm. When the cover is brought over the tilting table, lever 59 is oscillated (by means to be described) whereupon the pushing or tilting member 56 engages the upper portion of the top and tilts the cover toward the left, as viewed in Fig. 1, so that 20 it falls by gravity in right-side-up position on the tilting table and then in the next action of the machine the table is tilted as shown in Fig. 5 whereupon the cover slides by gravity down upon the top of a can body 69 which has been washed 25 and moved laterally to receive the cover by means also to be described.

For operation of the various feeding or can body and cover handling devices, there is a primary driving member in the form of a trans- 30 verse shaft 70 which may itself be driven in any convenient way—as shown, by an electric motor 71 mounted on horizontal frame members and connected to the primary driven shaft by a suitable gearing including sprockets and a chain 72, 35 a counter-shaft 73 supported in a frame bracket 74, and a worm 75 on that shaft engaging a worm gear 76 on the primary drive shaft. On one end of the main drive shaft is a crank 77 connected by a link 78 to an oscillating frame 40 79 pivotally mounted at 80 in a position below the line of advance of the can bodies; that is, at the left as viewed in Fig. 1. The upper end of this oscillating frame is connected, as by links 81 to slides or other devices for advancing the 45 can bodies. This frame is also connected by means of an angularly located link 84 to a lever 85 fulcrumed at 86 and arranged to swing in a horizontal plane to move the can bodies laterally therefrom to the main line of advance 50 while washing and to a position below the tilting table 63 above referred to. In this lateral movement the can bodies slide on a table 87 in a lower position at the discharge end of the machine, as best shown in Figs. 2 and 4. Lever 85 55 has a curved end 88 to engage a segment of the can body and when the body is in final position, as shown in full lines in Fig. 4, it is brought against the transversely directed end portion 89 of a locating and ejecting bar 90 which is mounted to reciprocate, longitudinally of the machine, in guides 91 and 92. Link 78 above referred to, for oscillating frame 79 is connected to a transverse bar 93 in the frame, and the inwardly extending end 94 of this bar is connected by a link 65 95 to the lower end of an upright lever 96. This lever is fulcrumed at 97 on a frame bracket 98 and its upper end is connected by a link 99 to the can cover feed slide 44 so that the can covers are advanced, step by step, coordinately with 70 the can bodies moving in a parallel line. Lever 96 is also connected by a short link 100 to the upper end of another upright lever 101, fulcrumed at 102 and having its lower end connected by a link 103 to the push rod 90 so that that rod is 75

reciprocated, in proper relation to the feed actions, whereupon the angularly bent locating and pushing member 89 of the rod ejects the can body with the cover located thereon rearwardly 5 from the table 87.

For operating the tilting table 63, the main drive shaft 70 has a cam 104 cooperating with a cam roll 105 on one end of a lever 106 fulcrumed at 102 and connected at its rearward end by an 10 adjustable link 107 to the tilting table at 108 so that the table is oscillated at proper times in relation to the cover feed movements.

The lever 59 carrying the push member 56 to tilt the covers to horizontal position, is operated 15 by lever 85 through a push rod 109 pivotally connected to the lower end of lever 59 at 110. This push rod is guided in a hole in a bracket 111 and its end is engaged by a flange 112 on lever 85 and held in such engagement by a spring 113 so 20 that when lever 85 is oscillated to position the can body, as shown in Fig. 4, the tilting member 56 is also actuated to tilt the can cover to horizontal position on table 63 and the table is then actuated as previously referred to and shown in 25 Fig. 5 to deliver the cover on top of a can body.

The general operation of the machine will be understood from preceding description in which the different operations or functions have been explained.

30 I claim:—

1. Can cover handling and washing mechanism comprising a guideway supporting can covers for linear advance in approximately edgewise upright position, means for advancing the covers step by 35 step in the guideway, a tilting table at the rear end of the guideway adapted to be tilted to discharge the covers, and a laterally operating pusher acting on the covers to tilt them to horizontal position on the tilting table.

40 2. Can cover handling and washing mechanism comprising a guideway supporting can covers for linear advance in approximately edgewise upright position, means for advancing the covers step by step in the guideway, a tilting table at the rear end of the guideway adapted to be tilted to 45 discharge the covers, a laterally operating pusher acting on the covers to tilt them to horizontal position on the tilting table, and means for tilting the table in coordinate relation to the advancing movements of the cover.

50 3. Can cover handling and washing mechanism comprising a guideway supporting can covers for linear advance in approximately edgewise upright position, means for advancing the covers 55 step by step in the guideway, a tilting table at the rear end of the guideway adapted to be tilted to discharge the covers, a laterally operating pusher acting on the covers to tilt them to horizontal position on the tilting table, and means for moving can bodies laterally to a position under the tilting table whereby a cover is deposited in upright position on each can body.

60 4. Can cover handling and washing mechanism comprising a guideway supporting can covers for linear advance in approximately edgewise upright position, means for advancing the covers step by step in the guideway, a tilting table at the rear end of the guideway adapted to be tilted to discharge the covers, a laterally operating pusher 65 acting on the covers to tilt them to horizontal position on the tilting table, means for moving can bodies laterally to a position under the tilting table whereby a cover is deposited in right side up position on each can body, and a push rod having a member to position can bodies for 70

receiving the covers and also acting to eject the can bodies.

5 5. A can cover washing machine comprising a frame, a horizontal rail to receive and support can covers by engagement with their necks, an upper horizontal guide rail to engage can cover tops and support the covers in a slightly tilted edgewise position, means for advancing the covers step by step, detent pawls preventing reverse movement of the covers, a tilting table adjacent the discharge end of the guide rails, means for operating the table, and a transversely moving lever having a pusher to engage the covers and tilt them to horizontal upright position on the tilting table.

10 15 6. Can cover handling mechanism comprising a guideway supporting can covers for linear advance in approximately edgewise upright position, means for advancing the covers step by step in the guideway, a tilting table at the rear end of the guideway, a laterally operating pusher acting on the covers to tilt them to horizontal position on the tilting table, and means for tilting the table in coordinate relation to the advancing movements of the covers.

20 25 7. A can cover handling machine comprising a frame, a horizontal rail to receive and support can covers by engagement with their necks, an upper horizontal guide rail to engage can cover tops and support the covers in a slightly tilted edgewise position, means for advancing the covers step by step, detent pawls preventing reverse movement of the covers, a tilting table adjacent the discharge end of the guide rails, and means for operating the table.

30 35 8. A can cover handling machine comprising a frame, a horizontal rail to receive and support can covers by engagement with their necks, an upper horizontal guide rail to engage can cover tops and support the covers in a slightly tilted edgewise position, means for advancing the covers step by step, detent pawls preventing reverse movement of the covers, a tilting table adjacent the discharge end of the guide rails, and means for operating the tilting table to deposit the 40 covers on can bodies positioned below the end of the tilting table to receive them and means to push the cans away from the tilting table.

45 50 9. Can cover handling mechanism comprising a guideway supporting can covers for linear advance in edgewise upright position, means for advancing the covers step by step in the guideway, means cooperating with the last named means for advancing a series of cans, means for moving the cans toward the end of the cover 55 guideway, and means at the delivery end of the cover guideway for applying the covers to the cans at a position in line with and below the cover guideway.

55 60 10. Apparatus for the purpose described combining a can guideway, cover guideway, positively actuated mechanism for depositing the cans in cover receiving position, and means including a tiltable member at the end of the cover guideway and on the same level therewith to receive 65 the cover and slide it to the can top as each can is moved below the end of said tiltable member.

65 70 75 11. Apparatus for the purpose described, combining means comprising a can guideway for advancing a series of cans, means other than the last named means comprising a cover guideway for simultaneously advancing a cover in the same general direction of the cans, a horizontal platform, positively actuated mechanism at the end of the can advancing guideway for 75

moving the cans to their cover receiving position, means including a tilttable member at the end of and at the same level as the cover guideway to receive the cover and slide it to the can top, and positively actuated mechanism comprising a member engaging the can body for moving the cans with their applied covers away from the cover-applying position.

12. Apparatus for the purpose described combining means comprising a can guideway for ad-

vancing a series of cans, means for horizontally advancing a series of covers in the same general direction as the cans are advanced, a horizontal receiving platform having a flat top surface at the end of the can and cover guideways and on which the cans are free to slide, means including a tilttable member to receive the cover and slide it to the can top, and means to push the can to a position below said member.

LESTER J. WILLIAMS. 10
